UNITED STATES PATENT OFFICE

2,614,495

FUEL INJECTION SYSTEM FOR REVERSIBLE
INTERNAL-COMBUSTION ENGINES

Poul Emil Wiene, Copenhagen, Denmark

Application June 24, 1946, Serial No. 679,016
In Denmark June 16, 1945Section 1, Public Law 690, August 8, 1946
Patent expires June 16, 1965

4 Claims. (Cl. 103—2)

1

In reversible internal combustion engines it has for the actuation of the fuel injection pumps been the general practice to use two different control cams, for ahead working and for astern working respectively, or the same control cam has been used for both directions of rotation, but it has then been necessary during the reversing to give the control cam an angular turn in relation to the crank shaft.

Fuel injection systems are, however, also known for reversible internal combustion engines in which neither the application of a double set of pump cams nor an angular displacement of the pump cams at the reversing is needed, care being taken while applying a single unalterable set of pump cams that a fuel oil pump, which at ahead working supplies fuel oil to a certain cylinder or a certain combustion space or groups of such cylinders or spaces, will at astern working supply fuel oil to another or other cylinders or combustion spaces.

The present invention relates to such an injection system which more particularly defined is of the kind where the communication between the various fuel oil pumps and the fuel injection valves served by the latter is controlled by control members, e. g. cocks, valves, slide valves, or distributors, which at the reversing are reversed or changed over in such a way that at astern working each fuel oil pump is connected to the injection valve or valves of another or other cylinders or combustion spaces than at ahead working.

The member driving the fuel oil pump is in that case so constructed that at astern working it can effect injection at the proper points for the particular other cylinder or cylinders or combustion spaces without the fuel oil pump being reversed. As normally the fuel oil pumps are driven by means of control cams, the part of the pump control cam which at ahead working forms the rear side or the descent is then so shaped that at astern working it can function as ascent.

The above mentioned cocks, valves, slide valves, or distributors which are changed over at the reversing are in many cases to remain in the same position during the working of the engine for a long time, viz. as long as the working is in the same direction, e. g. in a marine engine during the whole of the time when the ship goes ahead without being manoeuvred. The said control members are on account of this subjected to sticking so that it may happen that they cannot be moved, if suddenly a reversing of the engine is demanded, and that the reversing desired thus cannot be effected.

2

The purpose of the invention is to make an injection system of the said kind safe and reliable in its functioning by the said control members which are reversed at the reversing being made or mounted in such a way that one may be certain that they cannot, by sticking in the periods when the working of the engine takes place in one and the same direction and in which they consequently do not function, prevent a reversing from being effected when such a reversing is needed.

In accordance with this the invention is first and foremost characterized in that the said control members which are changed over at the reversing are arranged for being put into a motion, which is different to their normal motion while functioning, during the periods in which they do not function as reversing members.

The invention may be carried into effect in the way that the said control members which are changed over at the reversing, which members may e. g. be constructed as slide valves incorporated in the tops of normal fuel oil pumps, are furnished with or connected with a kind of rocking device by means of which the control members can be given a suitable motion preferably in another direction or in another way than the one in which the control members are moved at the reversing. By means of such a rocking device, it will be possible to ascertain or to control the state of the control members at any desired time. Such control may be made at suitable intervals and especially at a suitable time before manoeuvring is expected to take place. If the control members do not stick, it is of course good, but if they should stick then there will be time for remedying this calamity by again getting the control members operable so that they may function when the reversing is to be carried out.

The invention can also be carried into effect in the way that the said control members which are changed over at the reversing are connected with, shaped in, or form part of members, which during the working of the engine are constantly or often moved, as e. g. fuel pump pistons or contingently slide valves which distribute the fuel oil from a pump or a pump pressure pipe to several injection valves. By this embodiment of the invention is attained that, without having to be influenced by hand, the said control members are moved constantly or frequently during the working and will thus be prevented from sticking.

When the said control members are combined with the fuel oil pump pistons, these may in accordance with the invention be performed in

part in a way normal per se with oblique cutting-off edges for the determination of the length of the injection period, in part with recesses and/or bores out of regard to their functioning as the said control members which are changed over at the reversing, the pistons being connected with or under the influence of members, by means of which they can be adjusted, in part for ordinary regulation of the injection, in part for reversing of the engine.

In accordance with a further development of the invention each of or one or more of the said control members or of the pistons in the fuel oil pumps functioning as such control members may furthermore have recesses, bores, or similar shaped parts for the control of the communication conduit, the so-called astern conduit, from the pump which during astern working is to supply fuel oil to the injection valve which the particular control member or pump piston normally serves. This arrangement serves for avoiding the drawback as regards increased lost work of the fuel oil pumps and an irregular injection process (e. g. after-injection or so-called stealthy opening of the injection valve) which might arise when communication conduits of a greater length are used if these, while out of use, were only cut off at the end nearest the pertaining pump.

It is especially in such embodiments where long communication conduits (astern conduits) are used that the risk of accumulation of air asserts itself, which risk can be reduced or avoided, in part in a way known per se by the conduits being placed with a suitable declination, in part by utilization of the natural leakage of the slide valves for producing a constant slight oil flow through the conduits to an outlet, whereby the conduits are vented. As, however, the natural leakage will generally be insufficient for the said purpose, there may expediently in accordance with the invention be formed slits or fine channels in the slide valves, whereby a flow can be produced artificially to an outlet through the conduits, especially the conduits which may for a long time remain unused. The procuring of such an artificial flow will at the same time entail that the slide valves are kept oiled to a certain degree, which may also prevent them from sticking.

The invention is illustrated on the accompanying drawing, where

Fig. 1 schematically shows an injection system of the kind to which the invention refers, there being for the sake of simplicity only shown the application of the system for two cylinders in a two-stroke engine, of which besides the cylinders and the fuel oil pumps with the communication conduits is also shown the shaft with the pump cams, in side elevation.

Fig. 2 the pump cams, in end view.

Fig. 3 the pertaining crank positions,

Figs. 4, 5 and 6 in a similar way as Figs. 1, 2, and 3 an injection system of the said kind in a three-cylinder engine.

Fig. 7 likewise schematically another embodiment of a three-cylinder engine, where distribution slide valves are used.

Fig. 8 at a larger scale such a distribution slide valve with pertaining slide valve liner in longitudinal section,

Fig. 9 a section on line IX—IX in Fig. 8,

Fig. 10 part of an embodiment with a control slide valve incorporated in the top of a fuel oil pump and a rocking device for the said slide valve,

Figs. 11 and 12 sections on lines XI—XI and XII—XII respectively in Fig. 10,

Fig. 13 part of an embodiment with a fuel oil pump the piston of which is furthermore shaped as a control slide valve,

Figs. 14, 15, and 16 sections on lines XIV—XIV, XV—XV, and XVI—XVI respectively in Fig. 13,

Fig. 17 the surface of the piston in evolution, and

Figs. 18 and 19 likewise in evolution two other embodiments of a pump piston constructed as control slide valve.

The injection system shown schematically in Figs. 1—3 serves for in a simple way illustrating the principle of such a system by its application on two cylinders in a two-stroke engine, the cranks 1 and 2 of which are displaced 180° in relation to each other. A₁ and A₂ designate two fuel oil pumps driven by pump cams B₁ and B₂ respectively. The pertaining engine cylinders are designated by C₁ and C₂, and their injection valves are in communication each with its fuel pump through conduits L₁ and L₂, in which there are valves H₁ and H₂. Furthermore a pair of extra conduits l₁ and l₂ are mounted, the former of which connects the pump A₁ with the cylinder C₂, while the latter conduit connects the pump A₂ with the cylinder C₁. In the conduits l₁ and l₂ valves h₁ and h₂ respectively are fitted.

During ahead working the valves H₁ and H₂ are open, while the valves h₁ and h₂ are closed, so that the pump A₁ supplies the cylinder C₁ and the pump A₂ the cylinder C₂. At reversing the former valves are closed while the valves h₁ and h₂ are opened, so that now the pump A₁ supplies the cylinder C₂, while the pump A₂ supplies the cylinder C₁.

The shaft carrying the pump cams B₁ and B₂ has hereby not been adjusted by axial or rotational displacement but as it is in positive connection with the crank shaft it is only rotated in the opposite direction of before just as is the case with the crank shaft of the engine. The injection can nevertheless be effected in the proper way, the pump cams being in the well known manner constructed so that the part of them, which at ahead working forms the rear side or descent for one cylinder can function as ascent for another cylinder at astern working.

During the reversing there is, on the other hand, effected a reversing or change over of the valve system H₁, H₂, h₁, and h₂. Instead of valves, cocks or slide valves may be used or contingently a single slide valve or distributor.

In the schematically shown Fig. 1, the letters C₁ and C₂ may alternatively—instead of two different engine cylinders—designate the top end and the bottom end, respectively, of one and the same engine cylinder of a double-acting engine.

In Figs. 4—6 is shown how the injection system may be arranged for a three-cylinder engine, the cranks 1, 2, and 3 of which are displaced 120° in relation to each other. The designations used in Figs. 4 and 5 correspond to the designations used in Figs. 1 and 2.

During ahead working the valves H₁, H₂, and H₃ are open, while the valves h₁, h₂, and h₃ are closed, so that each of the three fuel pumps A₁, A₂, and A₃ supply fuel oil to the nearest cylinder, C₁, C₂, and C₃ respectively. During astern working the former valves are closed, while the latter are opened, whereby the pump A₁ will be made to supply the cylinder C₂, the pump A₂ the cylinder C₃, and the pump A₃ the cylinder C₁, viz. through the extra conduits l₁, l₂, and l₃, which

5

conducts will in the following be called astern conduits.

This embodiment suffers, however, from the drawback that e. g. the comparatively long astern conduit l_1 from the valve h_3 at the pump A_3 to the conduit l_1 , which leads to the cylinder C_1 , will also during ahead working be in communication with the said injection conduit l_1 to the cylinder C_1 from the fuel pump A_1 , which circumstance will cause an increase in the lost work of the fuel pump and reduce the regularity of the injection. Out of regard to this there may as shown in Fig. 4 be mounted an extra valve k_3 in the astern conduit l_1 at the end of the latter farthest from the pump A_3 , which valve opens and closes in time with the valve h_3 and contrary to the valve H_1 . In a similar way valves k_1 and k_2 may be fitted at the ends of the astern conduits l_1 and l_2 .

The valves k_1 , k_2 , and k_3 may be constructed as automatically acting non-return valves, and these may be provided with skirts, so that the pertaining astern conduits are wholly or partly relieved when the valves close.

On account of the fact that the three valves H , h , and k are to be actuated at the same time they may also be substituted by a slide valve which performs the functions of all the valves.

In the embodiment shown in Fig. 7 three such distribution valves G_1 , G_2 , and G_3 are mounted which substitute the nine valves shown in Fig. 4. Each of the fuel pumps is connected with its slide valve through a discharge conduit a_1 , a_2 , and a_3 respectively, and from each of the slide valves injection conduits c_1 , c_2 , and c_3 respectively lead to the pertaining engine cylinders. The slide valves are furthermore interconnected through conduits, of which the ones leading from the slide valve G_1 to the slide valves G_2 and G_3 are designated by g_2 and g_3 respectively.

In Fig. 8 one of the slide valves, viz. the slide valve G_1 is shown together with the pertaining slide valve liner and the conduits and channels terminating in the latter, there being besides the conduits a_1 , c_1 , g_2 , and g_3 already mentioned shown a pair of channels M , which serve as outlet conduits. The slide valve G_1 has ring-shaped turnings D and E besides two axial milled-out recesses F and F' situated diametrically opposite to each other, such as appears from Figs. 8 and 9.

In the position of the slide valve shown in Fig. 8 the oil passes from the pump A_1 through the conduit a_1 and the turning D to the conduit c_1 and from there to the cylinder C_1 , and the two other slide valves G_2 and G_3 lead in a corresponding manner the oil direct from the pumps A_2 and A_3 to the pertaining cylinders C_2 and C_3 respectively. If, however, the slide valve G_1 is displaced to the left in Fig. 8, so that the milled-out recess F is in line with both the conduit a_1 and the conduit g_2 , the oil from the pump A_1 will through the milled-out recess F be led to the slide valve G_2 through the conduit g_2 and from the slide valve G_2 to the cylinder C_2 , while the oil from the pump A_3 will through the conduit g_3 be led to the milled-out recess F' in the slide valve G_1 shown and from there through the conduit c_1 to the cylinder C_1 . Correspondingly the oil will from the pump A_2 be directed to the cylinder C_3 through the slide valve G_3 .

The turnings or grooves E serve for the accumulation of leak-oil from the turning D , which leak-oil can pass away through the conduit g_2 to the slide valve G_2 . Correspondingly, leak-oil

6

is led from the slide valve G_3 through the conduit g_3 to the slide valve G_1 , where through the milled-out recess F' it is led to the outlet M . Hereby a permanent venting of the astern conduits is caused.

The cocks, valves, or slide valves mentioned above, which are to be changed over at the reversing, are in accordance with the invention as already mentioned arranged for being able to be moved, e. g. at short intervals or a short time before manoeuvering is to be expected, so that one may control whether they stick or not.

In Figs. 10-12 part of a normal fuel pump is shown, in the top of which a slide valve G_1 has been incorporated, the function of which is similar to that of the slide valve G_1 in accordance with Figs. 8 and 9, but which at reversing instead of being displaced in its longitudinal direction is turned around its axis, viz. 90° , which turning is caused by means of the manoeuvering member designated by X . In this embodiment the slide valve may for the prevention of sticking be moved a little in its longitudinal direction. Normally it is held fast in the position shown in Fig. 10 under the influence of the eccentric V in combination with a spring R , but if one wants to try whether the slide valve is movable, it can be done by the handle Y connected with the eccentric V being turned in the direction indicated by the arrow, whereby the eccentric permits the slide valve to be displaced a short distance, which will happen at once on account of the oil pressure under the slide valve, so that he who makes the control can either hear the motion or feel it.

The designations used in Figs. 10-12 correspond to those used in Fig. 8, the conduit a_1 , however, having been dispensed with on account of the fact that the slide valve G_1 is incorporated in the pump A_1 proper. The suction opening of the latter is designated by S .

In the position of the slide valve G_1 shown in Figs. 10-12 the oil is led from the pump A_1 direct to the cylinder C_1 through the milled-out recess D in the slide valve and the passage c_1 in the liner. When the slide valve is turned 90° from the position shown, the lower part of the slide valve cuts off the communication to the passage c_1 , but at the same time a communication is through the milled-out recess D opened to the passage g_2 , so that the oil is led to the cylinder C_2 through the slide valve G_2 situated in the top of the fuel pump A_2 (not shown). At the same time there will through the milled-out recess F be established a communication between the passages g_3 and c_1 , so that the oil led from the pump A_3 through the slide valve G_3 (not shown) to the passage g_3 is through the milled-out recess F and the passage c_1 led to the cylinder C_1 . The passage g_3 can as shown in Figs. 10 and 11 expediently be divided and terminate in two places situated diametrically opposite to each other, so that a one-sided load of the slide valve is avoided.

In the embodiment shown in Figs. 13-17 the danger of sticking of the slide valve member is avoided or at any rate considerably decreased by the slide valve being formed in the fuel pump piston proper, which is constantly in motion during the working of the engine. The pump piston shown is in the ordinary way provided with two sets of oblique cutting-off edges K , but has furthermore a pair of milled-out recesses D which carry out the slide valve function, and furthermore there are a pair of milled-out recesses F and F' for the purpose of cutting off the astern conduit. The pump piston is shown at bottom

and in the starting position, the suction openings S being in line with the mouths of the milled-out recesses between the oblique edges K, so that the pump pressure space T will constantly be in communication with the suction openings S. If the piston is turned to one side, which corresponds to ahead working, the oil will through the milled-out recesses D be led to the passages c_{1a} , which lead to the cylinder C_1 , while, when the pump piston is turned to the other side, corresponding to astern working, the oil will be led to the passages c_2 , which lead to the cylinder C_2 . There might be only a single passage c_{1a} and a single passage c_2 , but these passages are expediently doubled out of regard to the relief of the piston for lateral pressure, such as is indicated in Figs. 15 and 17. During astern working the milled-out recesses F and F' which are interconnected through a transverse bore N establish a communication from the pump A_3 through the passage a_3 to the cylinder C_1 through a passage c_{1b} .

The mode of operation must be supposed to appear most clearly by viewing the evolution of the surface of the piston shown in Fig. 17, in which the eight holes in the pump liner S, S, c_{1a} , c_2 , c_{1a} , c_2 , a_3 , and c_{1b} are drawn in their proper places in relation to the piston, when the latter is at the bottom in the starting position. The upper milled-out recesses shown, which comprise the milled-out recesses between the oblique edges K and the milled-out recesses connected therewith, are constantly in communication with the pressure space T of the pump, while the two lower milled-out recesses F and F' which are interconnected through the transverse bore N are cut off from the pressure space T. If the piston is turned so that the suction openings S get in line with the lines 20—20, the mouths of the passages c_{1a} will get in line with the lines 20—21, i. e. move along these lines in relation to the pump piston, if this is imagined stationary and the liner movable up and down, so that the passages c_{1a} are thus constantly in communication with the pressure space T. During the part of the pump stroke where the openings S are cut off, the oil will thus be pumped through the passages c_{1a} to the cylinder C_1 . At the same time the passages c_2 will be cut off, as in relation to the pump piston their mouths move along the lines 22—23, and the communication between the passages c_2 and c_{1b} will likewise be cut off, as in relation to the pump piston the mouths of these passages move along the lines 23—24. By turning the piston to the opposite side the former communications will, on the contrary, be cut off, while the latter communications are open.

The construction of the fuel pump piston shown in Figs. 13-17 entails that the piston gets a rather considerable length. This may be avoided by omission of the lower milled-out recesses, a non-return valve as valve k in Fig. 4 being used as a substitute for these, but it may, however, also be avoided by the piston being constructed as shown in evolution in Fig. 18 or in Fig. 19.

In Fig. 18 the placing of the four necessary holes in the pump liner S, c_1 , c_2 , and a_3 are shown in the position which they take up in relation to the piston when the latter is at bottom in the starting position. The milled-out recesses to the left at the top are constantly in communication with the pressure space T of the pump, so that all the oil is pumped back to the suction passage. If the pump piston is turned to the right in Fig. 18, which is illustrated best if all of

the four holes are imagined moved to the left, the suction opening S will during part of the pump stroke be covered by the hatched surface to the left of the recess between the oblique edges K, so that the oil is from the pressure space T forced through the hole c_1 , which will have got in line with the milled-out recess D, and is led to the cylinder C_1 , corresponding to ahead working, while the holes c_2 and a_3 will be constantly cut off. If on the other hand the piston is turned in the opposite direction, the said holes being imagined moved to the right in Fig. 18, the suction opening S will during part of the pump stroke be covered by the hatched surface to the left of the milled-out recess D, for a longer or shorter time dependent on the angle of turning.

The oil will then escape through the hole c_2 , which gets in line with the milled-out recess D', and be led to the cylinder C_2 . At the same time 20 the hole a_3 , which is in communication with the fuel pump A_3 , will get in line with the milled-out recess F, so that the oil from the pump A_3 can flow to the cylinder C_1 through the bore N which connects the milled-out recess F with the upper 25 milled-out recess F', in line with which the hole c_1 will now be.

The milled-out recesses F and F' shown in Fig. 18 need at normal astern working not be as high as the whole stroke of the pump, the pump A_3 30 only working when the pump A_1 approaches and has nearly reached its bottom position. The case may, however, be imagined that the piston in the fuel pump A_1 sticks, which will then happen in the top position, and in that case the pump A_3 35 will not be able to get rid of its oil unless it is provided with a safety valve. Furthermore the height of the milled-out recess D' corresponds only to the effective pump stroke. The embodiment in accordance with Fig. 18 furthermore has the drawback that the pump piston is not balanced, as the large unsymmetrical milled-out recesses will produce a side thrust on the piston, so that the latter and the pump liner are subjected to an increased wear. In practice a construction will therefore be preferred which requires a somewhat greater building length, e. g. 40 as indicated by Figs. 13-17, where all the milled-out recesses are symmetrical around the axis. On the other hand the milled-out recesses need not be symmetrical in relation to a plane, as the cutting off edges for ahead and astern may e. g. 45 very well be different in pitch.

In Fig. 19 a still simpler construction of the pump piston than that in Fig. 18 is shown, the milled-out recesses F and F' in accordance with 55 Fig. 18 being omitted. In this case the astern conduit is either provided with a non-return valve for cutting it off, or such a cutting-off is completely omitted. The piston in accordance with Fig. 19 is in fact practically speaking balanced, the two milled-out recesses being placed diametrically 60 opposite to each other and their areas being equal or at any rate very nearly equal. In this construction there is only one suction opening S, but otherwise the principle and mode of operation correspond to those described in connection 65 with Figs. 13-17 and Fig. 18. One hole c_1 is shown in communication with the cylinder C_1 and two holes c_2 and c_2' with communication to the cylinder C_2 . Of these the hole c_2' is not at 70 small loads in constant communication with the pressure space T during astern working, but it serves for relieving the pump piston, as during ahead working it constantly counteracts the pressure from the hole c_2 .

The fuel pump pistons can e. g. by means of a gear transmission or in other suitable ways be moved by being actuated by a handle, the central position of which corresponds to the stop position or the starting position. When the handle is turned to one side, the pump is adjusted for supplying fuel oil for ahead working, while the cylinders get injections for astern working when the handle is turned to the other side.

I claim:

1. In a fuel pump, the combination of a cylinder having an inlet and a pair of outlet ports; a piston reciprocable in said cylinder; and a valve member in said cylinder having a passage therein for selectively connecting said inlet port with said outlet ports, respectively, when said valve member is in two positions relative to said cylinder, said valve member being adapted to have a first movement for adjustment about the longitudinal axis of said cylinder, and to have a second movement for adjustment axially, and by one of said movements to be brought into and out of said two positions to effect continuous supply of fuel by successive reciprocation strokes of said piston through the outlet port to which said passage is connected, and by the other of said movements to be conditioned for movement from one of said positions to the other one of said positions to prevent sticking of said valve member.

2. A fuel pump, as claimed in claim 1, in which said valve member constitutes a part of the said piston.

3. In a fuel pump, the combination of a cylinder having an inlet and a pair of outlet ports; a piston reciprocable in said cylinder; and a valve member in said cylinder having a passage therein for selectively connecting said inlet port with said outlet ports, respectively, when said valve member is in two adjusted positions relative to said cylinder, said valve member being adapted to be adjusted axially of the cylinder into and out of said positions, to effect continuous supply of fuel by successive reciprocation strokes of said piston,

through the outlet port to which said passage is connected, and said valve member being also adapted to be adjusted about the longitudinal axis of the cylinder to be conditioned for its axial adjustment, to prevent sticking of said valve member.

4. In a fuel pump, the combination of a cylinder having an inlet and a pair of outlet ports; a piston reciprocable in said cylinder; and a valve member in said cylinder having a passage therein for selectively connecting said inlet port with said outlet ports, respectively, when said valve member is in two adjusted positions relative to said cylinder, said valve member being adapted to be angularly adjusted about the longitudinal axis of the cylinder into and out of said positions, to effect continuous supply of fuel by successive reciprocation strokes of said piston, through the outlet port to which said passage is connected, and said valve member being also adapted to be adjusted axially of said cylinder to be conditioned for its angular movement, to prevent sticking of said valve member.
